UNITED STATES PATENT OFFICE.

GEORGE W. FENLEY, SR., OF TOLOSA, TEXAS.

HORSESHOE.

SPECIFICATION forming part of Letters Patent No. 267,855, dated November 21, 1882.

Application filed May 9, 1882. (No model.)

To all whom it may concern:

Be it known that I, GEORGE W. FENLEY, Sr., of Tolosa, Kaufman county, Texas, have invented a new and useful Improvement in 5 Horseshoes, of which the following is a full, clear, and exact description.

Reference is to be had to the accompanying drawings, forming part of this specification, in which similar letters of reference indicate corresponding parts in all the figures.

Figure 1 is a plan view of my improvement. Fig. 2 is a bottom view of the same. Fig. 3 is a sectional elevation of the same taken through the line $x-x$, Fig. 1. Fig. 4 is a 15 sectional front elevation of the same taken through the line $y-y$, Fig. 1; and Fig. 5 is a front elevation of the same opened.

The object of this invention is to facilitate the application of shoes to horses' feet, and 20 also to protect the hoofs of horses' feet from injury.

The invention consists in a horseshoe constructed with a base made in two parts, hinged together at their forward ends, and 25 having a cap, also made in two parts, attached to the base, the parts of the cap being provided at their upper forward corners with eyes and a fastening-staple, and the hinged parts of the base being locked in place by a screw- 30 rod passing through the hinged end of the base, whereby the shoe can be readily applied and detached, and will be securely held in place, as will be hereinafter fully described.

The base of the shoe is made in two parts, 35 A B, the forward ends of which are made wide, and are slatted transversely upon their inner edges to interlock with each other and form a hinge with three lugs, more or less. The pintle C of the hinge passes through all the lugs 40 of the parts A B, and may have a screw-thread formed upon its inner end to screw into the inner lug, or into a nut screwed upon its inner end, or may have its inner end headed down or riveted. The lower sides of the ends 45 of the lugs of the parts A B are beveled, as shown in Figs. 4 and 5, and the bottoms of the slots are correspondingly beveled, so that the parts A B cannot swing upward upon the pintle C farther than into a horizontal position, and cannot cause the shoe to pinch the 50 hoof.

To the outer edges of the parts A B of the

base are welded, soldered, riveted, or otherwise securely attached the parts D E of the cap, which parts are inclined inward and are 55 so formed as to fit the hoof snugly and neatly. The cap is made of thin iron, and the forward edges of its parts D E abut against each other, and have eyes F formed upon or attached to their upper corners to receive the arms of a 60 staple or bent wire, G. The staple G is locked in place in the eyes F by bending the ends of its arms, or by slotting the said ends and inserting a thin key, or in any other convenient manner. The shoe is further locked in place, 65 when upon the hoof, by a rod, H, which passes transversely through the hinged forward ends of the parts A B, and has a screw-thread formed upon its forward end to screw into a screw-thread in the bottom of the hole into 70 which the said screw-rod is inserted.

With this construction the shoe can be easily and quickly applied to and detached from a horse's foot by removing the screw-rod H and fastening G, and when applied to the 75 foot will be held firmly in place by the said screw-rod and fastening. This shoe has the further advantage of protecting the hoof and preventing the hoof from spreading or cracking.

Having thus described my invention, I claim as new and desire to secure by Letters Patent—

1. In a horseshoe, the base A B, made in two parts hinged to each other by parallel arms having beveled ends, and a pintle, C, 85 substantially as herein shown and described, whereby the upward movement of the said parts above a horizontal plane is prevented, as set forth.

2. In a horseshoe, the combination, with 90 the hinged base A B, of the two-part cap D E, having fastening F G, substantially as herein shown and described, whereby the shoe can be readily applied and detached and will be firmly held in place, as set forth.

3. In a horseshoe, the combination, with 95 the hinged base A B, having cap D E, of the screw-rod H, substantially as herein shown and described, whereby the said hinged parts are locked in place, as set forth.

GEORGE WASHINGTON FENLEY, SR.
